United States Patent Office

Des. 180,163

Patented Apr. 23, 1957

180,163

OYSTER CASE

Edwin F. Schild, Schiller Park, Ill.

Application June 4, 1954, Serial No. 30,819

Term of patent 14 years

(Cl. D80—11)

Fig. 1.

Fig. 2.

Fig. 3.

Fig. 4.

Fig. 1 is a top plan view of an oyster case embodying my new design;

Fig. 2 is a front elevational view;

Fig. 3 is a side elevational view; and

Fig. 4 is a perspective view of the same.

I claim:

The ornamental design for an oyster case, substantially as shown.
